UNITED STATES PATENT OFFICE.

THOMAS S. TAYLOR, OF BAKER, OREGON.

DEVICE FOR SUPPORTING A DISPLAY-CASE ON A CASH-REGISTER.

1,366,848.

Specification of Letters Patent. Patented Jan. 25, 1921.

Application filed May 10, 1920. Serial No. 380,415.

To all whom it may concern:

Be it known that I, THOMAS S. TAYLOR, citizen of the United States, residing at Baker, in the county of Baker and State of Oregon, have invented certain new and useful Improvements in Devices for Supporting Display-Cases on Cash-Registers, of which the following is a specification.

The object of this invention is to provide 10 a device for supporting a display-case from the top of a cash-register, and which will be simple in construction and readily installed in operative position.

A further object is to provide such a device which may be installed on the cash-register without marring or otherwise injuring the same, and which requires no change therein.

With these objects in view, the invention 20 resides, broadly stated, in supporting members of a peculiar shape adapting them to be positioned upon the top of a cash-register so as to hold a display-case.

The accompanying drawing clearly discloses an exemplary embodiment capable of carrying out the underlying principles of the invention. Like reference characters designate corresponding parts throughout the several views, which latter may be briefly 30 described as follows:

Figure 1 is a perspective view of the upper portion of a cash-register, showing the application of my invention thereto, and showing my device supporting a show-case;

Fig. 2 is a view in rear elevation of one of the two complementary supporting-devices;

Fig. 3 is a top plan view of one of said devices; and

Fig. 4 is a sectional view, on the line 4—4, 40 Fig. 2, looking in the direction of the arrows.

Referring, now, in detail, to the drawing:

Each of my two supporting devices is, preferably, a metallic casting, and, as shown in Fig. 1, said complementary supporting devices are adapted to seat upon the ends of the cash-register 1, at the top thereof.

Each supporting member has a base 2, having the bent terminals 7, 7 and carrying, laterally, pairs of integral, upwardly-projecting angles 3 and 13, the angles of each pair being parallel.

Depending from the base 2 is a flange 5,

having bent terminals 6, 6. The flange is apertured, at 10, 10, for the reception of screws 11, 11, which secure the supporting device to the side member 4 of the cash register.

The terminals 7, 7 are connected by a horizontal web 8, having, preferably, a curved outer longitudinal edge 9. The web is, in effect, a horizontal flange of the base 2.

In use, one of said supporting devices is secured upon each end of the cash-register side-member 4, at the top thereof, and firmly secured in position by the screws 11, 11. Two rectangular glass plates or panels 12, 12, forming the two sides of the display case, are then slipped vertically between two parallel flanges of each pair of angles 3, 13. Two glass plates 14, 14, constituting the ends 70 of the display-case, are then slipped vertically into position between the other two parallel flanges of each pair of said angles, the said glass plates fitting snugly between said angle-flanges, which thus support the plates firmly in position against accidental displacement. A fifth glass panel, constituting the bottom of the display-case, may be disposed horizontally upon the webs 8, 8 of the supporting bases 2, 2.

In compliance with the Revised Statutes of the United States pertaining to Letters Patent for mechanical inventions, I have described with great particularity a concrete or physical embodiment of the underlying principles of my invention; it being understood that changes may be made in the structure disclosed, within the terms of the appended claims, without departing from the spirit of the invention, or necessarily sacrificing any of its advantages.

Having thus fully described my invention, what I claim as new and desire to secure by Letters Patent of the United States is:

1. Means for supporting a display-case upon a cash-register, comprising twin supporting bodies each comprising a base attachable to the top of a cash register, and having spaced, parallel, upward-projecting members frictionally engageable with glass panels, constituting the sides and ends of the display-case, to support the same in a vertical position, and a flange depending from said base and apertured for the re-

ception of means for securing said flange to a cash register.

2. Means for supporting a display-case upon a cash-register, comprising twin supporting bodies each comprising a base attachable to the top of a cash register, and having spaced, parallel, upward-projecting members frictionally engageable with glass

panels, constituting the sides and ends of the display-case, to support the same in a vertical position, said base having a horizontal flange to support a horizontally disposed glass panel, constituting the bottom of a glass display-case.

In testimony whereof, I affix my signature. 15
THOMAS S. TAYLOR.
